UNITED STATES PATENT OFFICE.

EDWARD L. FARLEY, OF JONESBORO, ARKANSAS.

COTTON CLEANER.

Application filed January 14, 1928. Serial No. 246,810.

This invention relates to a cotton cleaner, and the primary object of the same is to provide a cleaner organization of a comparatively simple form that may be installed without materially interfering with the setting or other equipment, and, that may occupy the space now allotted to a standard upright cleaning feeder as employed by gin manufacturers, and to embody therein mechanism for directing cotton of a bolly character to a boll breaker, or for receiving the cotton direct without passing it through the boll breaker to eliminate dust, dirt and trash therefrom, so that when the cotton is delivered to a distributor, or emerges from the improved cleaner for further operation, as, for instance, supply to a gin stand, it will be in suitable condition for effective ginning and the production of a superior commercial sample grade of cotton.

A further object of the invention is to provide a cotton cleaner having therein means for preliminarily treating cotton of different grades, or for subjecting hully cotton to the action of a boll breaker, or the treatment of cotton which enters the cleaner without bolls or small portions of bolls without passing through the boll breaker, and to finally treat the cotton of either grade through the medium of a recleaning means consisting of a plurality of spiked cylinders or rollers with interfitting spike members and a lower screen, proportioned and assembled in such manner as to subject the cotton to further or recleaning treatment to materially separate dust, dirt and other foreign matter from the cotton before it is delivered to the distributor or directly to a gin stand, and to avoid deterioration or injury to the cotton treated.

A further object of the invention is to introduce between a recleaning means consisting of a series of spiked rollers located at the lower portion of the cleaner, a saw cylinder and a single spiked conveyer in advance of said cylinder and which receives the hully cotton which has been subjected to treatment by the boll breaker, the conveyer having the spikes set in spiral form in reverse position from each other and to the center, to pick the final locks of cotton from portions of hulls or other foreign matter descending to the said conveyer before the cotton thus operated upon by the saw cylinder will be subjected to the recleaning

means and delivery from the cleaner to a distributor or gin stand.

A still further object of the invention is to provide a rotary recleaning means in a cleaner closely associated with devices for preliminarily treating cotton to receive bolly cotton which has been partially treated, or cotton which is of such limited bolly nature as to require only the ordinary gin stand to handle the same, and also other cotton of a higher grade, and subject the same to final recleaning devices.

The present invention is more in the nature of a hull extracting cleaning feeder, that is, it is a feeder device adapted to receive therein such a quantity of cotton as may be necessary to supply the individual stand, the delivery being over the entire length of the machine, and thus avoiding the necessity of providing right- and left-hand machines, as is the common practice in nearly all gin machinery installations.

With these and other objects and advantages in view the invention consists in the construction and arrangement of the several parts which will be more fully hereinafter described and claimed.

In the drawings:—

Fig. 1 is a transverse vertical section through a cleaner embodying the features of the invention.

Fig. 2 is a broken sectional view taken in the plane of line 2—2, Fig. 1.

Fig. 3 is a broken sectional view taken in the plane of line 3—3, Fig. 1.

Fig. 4 is a detail diagrammatic view of a novel form of conveyer which receives the hully cotton and delivers the same to a lower saw cylinder.

The numeral 5 designates a housing which is to be constructed as an enclosure of this type and of a composite nature, or having a frame 5^a with partial sheet metal structures 5^b secured thereto at intervals and which will be hereinafter specifically referred to as contributing to the formation of passages and disposition of the several parts. At the upper extremity of the housing is an inlet 6 having therebelow oppositely disposed fluted rollers 7 driven by suitable interposed mechanism from a main shaft 8 extending longitudinally through the housing and having mounted therein suitable bearings. Above the rollers 7 are inwardly inclined deflection boards or chutes 7^a which direct the cotton

of whatever character towards the fluted rollers 7. Below these rollers 7 is a saddle 9 comprising oppositely inclined deflection board or chute members 9^a and 9^b, and an upper valve 9^c which will be operated by any suitable means from the exterior of the housing to throw the same either to the right or to the left to deflect the mass of cotton fed into the housing in either one of the two directions. Vertically disposed directly below the center of the saddle 9 is a stripper 10 in the form of a specific roller, a saw cylinder 11 directly beneath the stripper 10, a brush cylinder 12 at the right and above the said saw cylinder, and below the saw cylinder 11 there is another stripper 13, a second saw cylinder 14, and a brush cylinder 15, all rotating in the direction of the arrows on these several instrumentalities. At the right of the saw cylinder 11, below the brush cylinder 12, is a downwardly inclined deflection or chute board 16, and between the board chute member 9^b and the upper portion of the stripper 10 is a horizontal guard 17 to prevent material passing above the said stripper from beneath the said guard. At the upper left hand side of the housing adjacent to the inlet 6 is an air valve 18 which may be opened or closed, as desired and found necessary, and at the opposite side of the housing above part of the mechanism is another air inlet valve 19, these valves 18 and 19 being adjustable or operable to admit a certain amount of air. In the event that air currents are used to move the foreign matter in a downward direction, it will be understood that these valves controlling openings are in favorable positions in the housing to facilitate this operation, and the valve 19 is pivoted in such manner as to permit foreign substances, which may pass into the machine with the cotton, to be easily removed. The lower part of the housing is hopper shaped or forms an outlet hopper 20 which opens into a trough 21 in which is a suitable conveyer or other refuse removing means 22. The lower right hand side of the housing, which is part of the sheet metal enclosure 5^b, is inclined inwardly and downwardly towards the said trough 21 and forms the long side of the hopper.

As shown at the left side of the interior of the housing below the valve 18 and at a suitable distance from the saw cylinder 11 is a spiked roller 23 with a screen 24 around the lower portion of the same and in adjacent cooperative relation to a boll breaker 25 comprising a toothed head 26 with an adjusting screw 27 attached thereto and having an exteriorly located and operable hand wheel or analogous device 28 bearing in the adjacent side portion of the housing. This boll breaker may be withdrawn by adjustment from cooperative adjacency to the spiked

roller 23, or it may be moved inwardly to perform its function or to operate as a crushing means with the said roller 23 and open and crush the bolls or portions of bolls that may be fed thereto. From the inner lower extremity of the screen 24 downwardly to the upper extremity of a screen 29 around a spiked roller 30, similar to the roller 23, is an outwardly and downwardly inclined deflection board or chute 31 which carries the refuse material passing through the screen 24 downwardly outside of the screen 29 and finally to the trough 21 and removing or conveying means 22 in the latter. In advance of the roller 30, and at a suitable distance below the deflection board or chute 31, is a deflection board or chute 32 which extends from its upper end to a point close to the saw cylinder 11 and terminates adjacent to the upper portion of the roller 30. Meeting the lower extremity of the screen 29 is the upper terminal of a screen 33 which extends downwardly and around the lower portion of a spiked conveyer 34 which stands adjacent to and in cooperative relation with the lower saw cylinder 14. This conveyer is in the form of a roller with spikes secured therein, and said conveyer serves as the final separation means of the portions of hulls to which the cotton locks still cling and from which the cotton is separated. The spikes 35 in this roller are set in spiral form in reverse inclined position from the center to the ends, and by this means the portions of the hulls with the locks of cotton still clinging thereto are moved across the saw cylinder 14, the cotton being taken up by the said saw cylinder 14 and separated from the portions of the hulls, and the latter together with any foreign matter that may pass down to this spiral conveyer 34 for final outlet into the lower hopper 20 and trough 21 for conveyance out of and away from the cleaner. All of the cotton which passes down to the second or lower saw cylinder 14 is taken up by the latter and the hulls or other matter that has a tendency to go over the saw cylinder with the cotton are kicked back by the stripper 13 and the cotton subjected to the action of the brush cylinder 15 and deposited on the outwardly and downwardly inclined deflection board 37 which terminates at its lower end at the inner terminal of a lower screen 38 arranged around the lower portion of a recleaning means consisting preferably, of a series of three spiked rollers 39, 39^a and 39^b, the screen 38 following around the lower portion of said rollers immediately above the downwardly inclined sheet metal wall or member of the housing 5^b adjacent thereto, said screen terminating at the upper end of the inner wall 40 of a hood or side outlet 41 which is adapted to be located over a gin stand roller box below and with which the improved cleaner is associated. The reclean-

ing mechanism comprising the rollers 39, 39^a and 39^b and the lower enclosing screen 38 therefor are so arranged that the spikes thereof are close enough together to pass the 5 cotton as it is fed to the lowermost roller 39 of the series from the deflection board 37 and be fed downwardly between and pass below the rollers and progressed by the spikes 39^c of the rollers over the screen 38 in 10 a thin mass and moved along said screen by the spikes of the rollers and free of the cores or body cylinders 39^d of the rollers, while the dust and dirt will pass through portions of the said screen 38 below, so that when the 15 cotton reaches the outlet, it will be materially free of foreign matter and be in first class condition for operation thereon by ginning. As shown, the top end 42 of a gin stand, as now commonly built, is represented, and 20 from this top of the gin stand are supports 43 and 44 by which the improved cleaner is applied and supported relatively to the gin stand, the dotted line 45 indicating a center line through the huller roller box of the gin 25 where the cotton is ordinarily received for handling and treatment by a gin. While the cleaner is represented as being applied in connection with a gin it is not to be understood that the cleaner in its application is 30 thus specifically limited, as it can be used in other ways or connections in the preparation of cotton. It may be used in connection with unloading and cleaning devices for final delivery into places of storage. Wherever 35 desired and found necessary, the parts may be hinged, as, for example, at 46 and 47 of the upper portion of the hood, to accommodate closing or reducing the said hood, there being a closing-off valve 48 for the hood 41 40 hinged at 49 and illustrated in full and dotted lines to demonstrate its operation, and by means of this valve a temporary cessation of feed may be obtained.

Cotton that is not sufficiently hully to 45 require more than the ordinary gin stand to handle and discharge it, and other cotton of higher quality, is delivered directly to the lower roller 39, the valve or gate 9^c is set as shown in full lines in Fig. 1, so 50 that this cotton is passed downwardly over the deflection board or chute member 9^a to and under the said lower spiked re-cleaning roller 39, and then continues to be passed under the remaining rollers 39^a and 39^b, and 55 is discharged from the cleaner through the hood 41 to the gin stand roller box. The cotton passing under the rollers 39, 39^a and 39^b will be so thin that air may readily 60 pass therethrough and carry off the dust and trash eliminated and which finds its outlet through the screen 38 onto the adjacent lower member or floor 5^b, and is directed downwardly and inwardly thereby 65 to the trough 21 which may have, as heretofore indicated, the conveyer 22 therein,

or this conveyer may be replaced by an air pipe under suction influence, which is an obvious and well known expedient in the art of handling or carrying away foreign matter eliminated from cotton. In the 70 event that the cotton is bolly to an extent greater than that which would be successfully handled and delivered directly to the gin stand, the valve 9^c is thrown over to the right, as shown in dotted lines, and 75 the bolly cotton then passes downwardly over the chute member 9^b to the spiked roller 23, where it may be acted upon by the boll breaker 25. It then passes downwardly to the next spiked roller 30 below, 80 and thence to the spirally spiked conveyer 34 for operation upon by the lower saw cylinder 14. The cotton is delivered across the space between the upper saw cylinder 11 by the spiked roller 23 and thence downwardly to the next roller 30, as just explained, and then acted upon by the upper saw cylinder 11 and passed therefrom where a considerable portion of separation of the 85 cotton from the hulls takes place, and the mass then passes down to the spiked roller 30. The hully cotton that engages the spiked roller 23 will be delivered across the space between the latter roller and the saw cylinder 11, and through the action of the 90 stripper 10 will be thrown back into the space or passage between the said upper saw cylinder and the said spiked roller 23, then gravitating over the board 32 to the spiked 95 roller 30. Such foreign matter as is taken out or eliminated by the roller 23 passes through the screen 24 and falls to the exit or trough 21 having therein the conveyer 100 105 22 or other analogous removing means. There will be more or less sifting operation 105 of the foreign matter passing downwardly with the cotton, such as small pieces of hulls and other material discharged from the cotton during passage through the space between the upper saw cylinder 11 and the 110 board 32 to the spiked roller 30, and also below the deflection board or chute 32 as the mass passes to the conveyer 34. By this means a material advantage will result 115 in the production of the sample. A given percent of the said cotton will be separated by the upper saw cylinder 11, as above noted, and the foreign matter with the residue of cotton thrown off from the saw cylinder 11 by centrifugal force and the operation of the stripper 10 will finally gravitate and come in contact with the roller 30, where 120 the operating results are similar to roller 23. When portions of hulls having cotton locks still clinging thereto reach the spirally toothed conveyer 34 they are caused to traverse the saw cylinder 14 from the ends towards the center thereof by the said spiral conveyer, with the result that the entire, 125 or practically the entire, hull residue will 130

be removed before the cotton mass is taken up by the saw cylinder 14 and delivered to the deflection board or chute 37, and by the latter to the lower roller 39 of the 5 recleaning series of rollers 39, 39^a and 39^b, any hull particles chanceing to come over with the cotton being kicked back by the stripper 13. The shells or trash removed by the conveyer 34 and lower saw cylinder 10 14 pass down through a central opening 38^a in the screen 38 and fall into the hopper 20 being carried off as heretofore explained. Both brush cylinders 12 and 15 cooperate or function with their respective saw cylinders 11 and 14 in a manner well known in this art.

One of the most important features of the present improved cleaner is the spirally spiked conveyer 34 arranged adjacent to the 20 lower saw cylinder 14 and by which cotton locks and portions of hulls are detached and the cotton caught up and thrown over the saw cylinder of the lowermost roller 39 of the set of recleaning rollers 39, 39^a and 39^b. Another important feature of the present 25 invention is the recleaning rollers 39, 39^a and 39^b located for receiving the cotton, as hereinbefore described, so that when the cotton is delivered from the last of the series 30 of rollers 39^b to the side outlet or hood 41, the cotton will be practically free of all particles of hulls and other foreign matter. The spikes 39^c of the rollers pass adjacent to the spikes of the succeeding rollers throughout 35 the series of rollers 39, 39^a and 39^b, there being just enough space between the spikes to afford a clearance of the said spikes during rotation of the rollers, and, as a consequence, the cotton is held below the axes 40 of the rollers during its traverse of the entire series of rollers. As a consequence, when the cotton reaches the hood 41 and is deposited in the gin, it has not been wasted and the fibers thereof have not been twisted 45 or broken, because the cotton is prevented from passing between these recleaning rollers. The upward inclination of the group of recleaning rollers 39, 39^a and 39^b is especially effective in performing the cleaning 50 operation, as the cotton is forced to move in an upwardly inclined direction with some

little resistance which will be more effective in separating the dirt, dust and trash therefrom before delivery of the cotton to the side outlet or hood 41.

From the foregoing it will be seen that the parts of the cleaner are comparatively simple in their construction and operation, and when air currents are admitted through the valves and allowed to descend or be directed downwardly by the operation of the mechanisms the cotton will be more thoroughly cleaned, and especially after leaving the recleaning rollers 39, 39^a and 39^b where the cotton is maintained in a thin stream-like mass and prevented from packing and occluding the passage of the air currents therethrough.

It is proposed to modify the proportions and minor details of construction of the several parts within the scope of the appended claim, and to employ such mechanism for connecting and operating the several parts to impart thereto the purposed direction of rotation as may be desired and well known to those skilled in the art.

What is claimed as new is:

A cotton cleaner including a casing having an upper centrally disposed inlet and a side outlet, two superposed strip, brush and saw combinations, a saddle interposed between the upper combination and the inlet, the apex of said saddle being approximately below the center line of the inlet, a valve cooperating with the apex of the saddle and the casing to direct the cotton and hulls from the inlet to either side of the saddle, a series of boll breakers mounted in the casing at the opposite side of the outlet of the casing to break the bolls when the cotton and bolls are diverted for operation upon by the breakers and the combinations, and a series of spiked rollers and screens interposed between the outlet and the combinations and upon which the cotton and hulls may be directly fed from the saddle and to which the cotton is fed after treatment by the combinations.

In testimony whereof I have hereunto set my hand.

EDWARD L. FARLEY.
